UNITED STATES PATENT OFFICE.

GUNNAR ELIAS CASSEL, OF STOCKHOLM, SWEDEN, ASSIGNOR TO ARTUR LEFFLER, OF DJURSHOLM, SWEDEN.

ELECTRICAL AGRICULTURAL SYSTEM.

Application filed March 2, 1923. Serial No. 622,420.

To all whom it may concern:

Be it known that I, GUNNAR ELIAS CASSEL, a citizen of the Kingdom of Sweden, residing at Stockholm, Sweden, have invented 5 new and useful Improvements in Electrical Agricultural Systems, of which the following is a specification.

This invention relates to wire systems for supplying current to electrically driven 10 traction engines and similar self-propelling vehicles for agricultural purposes.

The wire systems as hitherto proposed for supplying current to such vehicles have required complicated mechanisms for the collection of the current in order to prevent short-circuit and entangling of the current collecting wires operating between the stationary line system and the vehicle.

According to the present invention such 20 drawbacks are avoided by means of a simple and cheap construction of wire system. One feature of the invention involves the provision of a stationary network comprising a plurality of over head lines extending parallel to each other on the field to be cultivated and each involving one or more bare wires.

Another feature of the invention involves the provision of a current collecting device comprising a bridge, mounted between two 30 such over head lines so as to be capable of being moved along said lines in contact with the wires thereof, said bridge being so connected with the vehicle as to be moved with the latter on its way along the lines. The 35 connection between the bridge and the vehicle is, furthermore, of a nature to permit turning or lateral movements of the vehicle without causing any entangling or short-circuit.

40 In the drawing one embodiment of the invention is illustrated. Fig. 1 is an end view of a wire system including two stationary lines, each comprising a single wire. Fig. 2 is a plan view of part of said wire system. Fig. 3 is a vertical section and Fig. 4 is a plan view of the current collecting device of the wire system shown in Fig. 1.

50 In Figs. 1 and 2 I have illustrated part of a stationary network, comprising two parallel over-head lines, each involving a single bare wire 1 and 2, respectively. One of said wires is connected to the positive

terminal of a continuous current source and the other wire is connected to the negative 55 terminal of the same source. The two lines are situated at a comparatively great distance apart on the field to be cultivated. The traction engine 3 supports a pole 4 carrying two rope pulleys 5 and 6, respectively. Each of said pulleys supports a wire 7 and 8, respectively, connected to a current collecting roller or disk 9 and 10, respectively, engaging its corresponding over head wire 1 and 2, respectively. The 60 design and construction of the rope pulleys is more clearly shown in Figs. 3 and 4. The pole ends at its top in a pivot pin 11, on which is mounted a hub bushing 12. The pulley 6 is rigidly secured to said bushing 65 and also electrically connected thereto. The pulley 5 is rotatably mounted on the bushing 12 and electrically insulated therefrom. The two pulleys are connected together by means of a spiral spring 13 tending to rotate them relatively to each other in a manner to maintain the wires 7, 8 under continuous tension. The wires are oppositely wound around the pulleys so that one of them will be unwound from its respective 70 pulley and the other will be wound on to its pulley, when the pulleys are rotated simultaneously around the pole 4, due, for instance, to the propelling of the traction engine in a direction parallel to the direction of the wires 7 and 8. The wire 7 is conductively connected to one terminal of the power motor of the traction engine by means of pulley 5 and a separate wire 14, while the wire 8 is conductively connected 75 to the other terminal of said power motor by way of pulley 6, bushing 12, and pole 4.

With a wire system as described above the traction engine is able to move within the zone enclosed between the two wires 1 80 and 2 without causing any entangling or short circuit of the various wires. If the field is very large, there may be provided as many parallel wires as is necessary to enclose the whole field. Alternate wires are 85 in such case connected to positive and negative current source, respectively. The wire system, however, may not only be used for continuous current, as assumed in the above 90 description, but may also be used in connection with alternating current. The sys- 95 100 105

tem shown in Figs. 1-2 may, of course, be used without any modifications for single-phase alternating current.

What I claim is:—

6 A wire system for supplying current to electrically driven self-propelling vehicles for agricultural purposes, comprising in combination a plurality of stationary bare wire over head lines extending parallel to each other on the field to be cultivated, a current collector bridge movable along two such lines in contact therewith, said bridge including a sliding contact on each of said

lines, two wire pulleys on the vehicle, and two separate wires, each extending between one of said sliding contacts and one of said pulleys, said pulleys being mounted so as to be capable of rotation relatively to each other, and connected together by a spring tending to rotate the pulleys relatively to each other in a direction to hold their respective wires under tension. 15

In testimony whereof I have signed my name.

GUNNAR ELIAS CASSEL.
